DESIGN FOR A BOILER SECTION

Robert C. Cross, Western Springs, Ill., assignor to
Sears, Roebuck and Co., Chicago, Ill., a corpora-
tion of New York

Application August 16, 1946, Serial No. 132,580

Term of patent 14 years

(Cl. D81—2)

To all whom it may concern:

Be it known that I, Robert C. Cross, a citizen of the United States and a resident of Western Springs, in the county of Cook and State of Illinois, have invented a new, original, and ornamental Design for a Boiler Section, of which the following is a specification, reference being had to the accompanying drawing, forming a part thereof.

The figure is a perspective view of a boiler section embodying the novel and artistic features of my new design.

The other side of the boiler section is substantially the same as the side shown in the figure of the drawing.

I claim:

The ornamental design for a boiler section, substantially as shown and described.

ROBERT C. CROSS.
